Primary Examiner — Thomas Johannes*Assistant Examiner* — Catherine S Posthauer(74) *Attorney, Agent, or Firm* — Womble Bond Dickinson (US) LLP(57) **CLAIM**

The ornamental design for a lid, substantially as shown and described.

DESCRIPTION

FIG. 1 is a top perspective view of a lid showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines are shown for the purpose of illustrating parts of the lid that form no part of the claim.

1 Claim, 4 Drawing Sheets(56)
